UNITED STATES PATENT OFFICE.

HRANT G. ANTARAMIAN, OF KENOSHA, WISCONSIN.

STRIPING MACHINE.

1,425,312.

Specification of Letters Patent. Patented Aug. 8, 1922.

Application filed September 9, 1920. Serial No. 409,119.

To all whom it may concern:

Be it known that I, HRANT G. ANTARAMIAN, a citizen of the United States, residing at Kenosha, county of Kenosha, State 5 of Wisconsin, have invented a certain new and useful Improvement in Striping Machines, and declare the following to be a full, clear, and exact description of the same, such as will enable others skilled in the art 10 to which it pertains to make and use the same, reference being had to the accompanying drawings, which form a part of this specification.

My invention has for its object to produce 15 a simple and novel machine for forming stripes or bands accurately and expeditiously on rods, tubes or the like.

The various features of novelty whereby 20 my invention is characterized will herein- 25 after be pointed out with particularity in the claims; but, for a full understanding of my invention and of its object and advantages, reference may be had to the following detailed description taken in connection 25 with the accompanying drawings, wherein:

Figure 1 is a side elevation of a machine constructed in accordance with a preferred form of my invention;

Fig. 2 is a section taken approximately on 30 line 2—2 of Fig. 1;

Fig. 3 is a section taken approximately on line 3—3 of Fig. 1;

Fig. 4 is a vertical section on an enlarged scale through the lower part of the machine 35 adjacent to the manual controller for the machine;

Fig. 5 is a plan view of the automatic stop device for the rotating carrier;

Fig. 6 is a vertical section through one of 40 the upper work-supports, on an enlarged scale;

Fig. 7 is a side elevation of one of the lower rotatable work supports and a fragment of the stop mechanism shown in Fig. 45 5; and

Fig. 8 is a modified form of lower work support adapted to grasp the exterior of a rod or tube.

Referring to the drawings, 1 represents a 50 horizontal flat base above which is a horizontal ring-like plate, 2, having a section removed therefrom on the front side. Between the members 1 and 2 is a horizontal table, 3, which may conveniently take the 55 form of two parallel spoked wheels fastened together. The members 3 is fixed to a rev-

oluble vertical rod, 4. As best shown in Fig. 2, there are revolvably mounted at regular intervals on the under side of the table a series of horizontal pulleys, 5, four such 60 pulleys being illustrated. These pulleys may conveniently be driven by a belt, 6, which, in the arrangement shown, passes over three of the pulleys, around a pulley, 7, on a main driving shaft located at one 65 side of the gap in the member 2 and over idler pulleys, 9 and 10, mounted respectively on the base 1 at the other side of the gap in the plate 2 and on the plate. The pulleys, 5, may conveniently be held against vertical 70 displacement by locating them between the upper and lower halves of the rotatable table. The axle, 11, of each of these latter 75 pulleys projects downwardly through and below the lower half of the table and upwardly through the upper half; the upper end being provided with a suitable holder for the lower end of a rod or a tube. The holder may take the form of a steep pyramid as shown at 12 in Fig. 7, so as to enter the 80 lower end of a piece of work in the form of a tube and bite into it sufficiently to make the work turn with the pulley. Another form which the holder may take is shown in Fig. 8, the holder in this instance being in the 85 form of a conical socket, 13, having sharp internal ribs or projections, 14, which will grip the bottom exterior edge of a tube or the bottom edge of a rod and clutch the same to the pulley.

On the upper end of the rod, 4, is an upper work-supporting plate, 15, slideable vertically on the rod but held against rotation relatively thereto by means of a key, 16, extending lengthwise of the rod or otherwise. 95 The member 15 has a series or work-engaging members each lying directly above one of the lower work-holders, the upper members being adapted to keep tubes or rods in vertical positions while permitting them to 100 rotate on their axes. One of the upper work-engaging members, adapted to enter the upper end of a tube is illustrated in detail in Fig. 6. In this instance the bearing member consists of a pin, 18, slideable in a 105 vertical bearing, 19, carried by the part 15, the pin having on its lower end a conical head, 20. A spring, 21, in a chamber in the bearing 19 holds the pin down but permits it to be raised in placing a piece of work in 110 position or taking it out of the machine. The member 15 may be raised and lowered

to suit the length of the work. In Fig. 1 tubes, A, of medium length are shown in position in the machine, while the member is shown in dotted lines in a raised position 5 which it would occupy if the work were in longer pieces.

When the main shaft is rotated, by a belt, 22, or otherwise, the several rods or tubes are rapidly revolved so that if abrasive 10 strips are held against them stripes or bands will be formed on them. One of the features of the present invention has to do with the handling of the abrasive strips so as to secure rapid, accurate results. For the sake 15 of simplicity I have shown only a single strip but any number may of course be employed depending upon the number of stripes or bands desired. The abrasive strip is indicated at B in Figs. 1 and 2. It is wound at one end on a spool, 23, mounted at one end of the arc-shaped frame member, 2, from which spool it is carried past three of the 20 pieces of work into a pair of feed rolls, 24 and 25, on the other end of the member 2. It is desirable that the strip have a considerable area of contact with each piece of work during the abrading process and that it be carried clear of the work during the 25 shifting of the work as will hereinafter be described. Therefore I carry the strip over a series of guides, 26, 27, 28 and 29, on each of three horizontally-swinging arms, 30, mounted ninety degrees apart at the sides and rear of the frame member 2 adjacent to the table so as to lie in the vicinity of three of the pieces of work when the table is in any one of four predetermined angular positions. The guides, 27 and 28, are so positioned that when the arms are swung inwardly as shown in full lines in Fig. 2, the abrading strip is deflected outwardly by the pieces of work and engages each piece of work throughout a considerable angular 40 length. When the arms are swung outwardly as shown in dotted lines the deflected portions of the strip afford sufficient slack to permit the strip to be carried clear of the work without being torn or stretched. 45 The remaining mechanism of the machine serves to feed the strip gradually so as constantly to present new wearing surfaces to the work, to hold the table stationary while the stripes or bands are being formed, to 50 swing the arms, 30, in and out in proper time relation to the successive quarter turns of the table to permit each piece of work to be carried from the starting point at the front of the machine through three working positions and then back to the starting point, and automatically to stop the mechanism excepting the rotating holders whenever the table has made a complete rotation. 55 A secondary driving shaft, 31, extends approximately radially across the base from

a point adjacent to the driving shaft, 8, to the vicinity of the vertical shaft, 4. Between the shafts 8 and 31 is a gearing the driven member of which, 33, is loose on the shaft 31 and is adapted to be coupled thereto 70 by a suitable clutch, 34. The movable element of the clutch is adapted to be shifted back and forth lengthwise of the shaft 31 by a suitable actuating lever, 35, pivotally mounted between its ends at 36. When the 75 lever is in the position shown in full lines in Fig. 3, the clutch is in and the shaft 31 revolves. When the lever is swung in the clockwise direction as viewed in Fig. 3 the clutch is thrown out. In order to throw 80 the clutch in I have provided a wedge-shaped actuator, 37, as best shown in Fig. 4, which extends down behind one end of the lever and, when pressed down by the operator, swings the lever in the direction to 85 throw the clutch in. A spring, 38, serves normally to hold the actuator elevated so that the clutch may be thrown out automatically as will hereinafter be explained.

The shaft, 31, has thereon a worm, 40, meshing with a toothed wheel, 41, loose on the vertical shaft 4. The worm also meshes with a horizontal toothed wheel, 42, supported by the base. The wheel, 41, meshes with an idler wheel, 43, which in turn is intermeshed with two wheels, 44 and 45, lying on opposite sides thereof, the wheels 44 and 45 being similar to each other and to the wheel 42 so that all three of these wheels will be driven at the same speed when the shaft 31 is turned. The wheel 42 meshes with an idler wheel, 46, which in turn meshes with a wheel, 47, fixed to the lower end of one of the rolls, 25, which feed 90 the abrasive strip. Therefore, when the shaft 31 rotates it causes the feed rolls to turn slowly. On the wheel 47 is an upwardly-projecting pin, 48, which is so located that in a predetermined angular position of the wheel it will engage with one end of the clutch lever, 35, as illustrated in Fig. 3 and, as the wheel continues to revolve, will swing the lever into a clutch-releasing position so as to stop the shaft 31. The wheel, 47, is 95 similar to the wheels 42, 44 and 45, so that whenever, after the machine has been started, these wheels make a complete revolution, they are automatically stopped and will not start again until the clutch actuator, 37, is depressed.

In the vicinity of each of the toothed wheels, 42, 44 and 45, is placed an upright post, 49, which is revolvably supported by the members 1 and 2 and projects upwardly 100 through the latter member. Each of these posts carries a radially-projecting arm, 50, the free end of which is connected to the corresponding wheel by means of a link or connecting rod, 51, in such a way that the 105

wheel becomes a crank which oscillates the corresponding post when the wheel is rotated. The effective length of the arms 50 may be adjusted in any suitable way, conveniently by causing the arms to extend entirely through the posts and locking them in any desired positions by means of suitable set screws, 52, or the like. At the upper end of each post is an arm, 53, which may be similar to and adjustable in the same way as the arms 50. Each of the members 53 has an upwardly-projecting pin or finger, 54, engaged with the corresponding swinging member, 30, through which the abrading strip is threaded; the pin, 54, engaging the swinging member at a considerable distance from the pivot 55, of the swinging member so that, whenever the post is oscillated, it produces a similar oscillation in the corresponding member 30.

It is necessary that the rotating work-carrying table be always brought to rest with the pieces of work in operative relation to those portions of the abrading strip threaded through the swinging members 30. I have therefore provided the automatic stop which is best shown in Figs. 3 and 5. The stop comprises a horizontally-swinging Z-shaped lever, 56, supported from the base by a pivot or bearing, 57, arranged at about the middle of the lever, together with a bar, 58, connected at its middle to the front end of the lever 56 by means of a link, 59, and connected at its rear end to the rear end of the lever 56 by a link, 60. A spring, 61, between the members 56 and 58 tends to spread them apart as far as the links will permit. On the front end of the bar, 58, is an upward projection, 62, which normally lies in the paths of the lower ends of the axles of the lowermost work holders as best shown in Figs. 5 and 7. Therefore, whenever the table is rotated in the clockwise direction as viewed in Figs. 2 and 3, it travels until one of the axles, 11, strikes against the projection 62 and the rotation of the table will then cease. In order to release the table so as to permit it to continue its rotation I have placed on the toothed wheel, 41, on the vertical shaft, 4, a suitable part which, once during each revolution of the wheel 41, will engage with the adjacent end of the lever 56 and swing the stop mechanism from the position illustrated in full lines in Figs. 3 and 5 to the position illustrated in dotted lines in Fig. 5; thus drawing the projection 62 inwardly toward the vertical axis of the machine and clear of the axle with which it has been in engagement. The wheel 41 is similar to the wheels 42, 44, 45 and 47 so that a definite time relation is maintained between the swinging in and out of the strip-carrying arms, the starting and stopping of the table, and the automatic throwing out of the clutch for the worm shaft. The rotation of the

table is always in the clockwise direction as viewed in Fig. 2 and, by causing the belt 6 to run in this same direction, the belt will tend to rotate the table when free to do so. Furthermore, by causing the weight of the loaded table to rest upon the toothed wheel 41, a frictional driving connection is secured between this wheel and the table which will cause the table to rotate slowly whenever it is free to do so. This frictional driving connection may conveniently be accomplished by fixing on the lower end of the vertical shaft 4 a suitable collar, 63, resting on the toothed wheel 41. This collar may conveniently be in the form of a ratchet wheel engaged by a spring-pressed pawl, 64, carried by the wheel 41. The pawl is set in such a way that the wheel 41 may move independently of the vertical shaft in the direction in which the worm shaft tends to drive the wheel, but it prevents backward movement of the table and also acts in the manner of a brake. The pawl may conveniently be used as the part carried by the wheel 41 for engagement with the lever 56 of the stop device.

The operation of the machine.—Assuming that a single band or stripe is to be produced on a lot of tubes of the same length, the top plate, 15, of the machine is raised high enough to permit four of the tubes to be set into the machine as heretofore described; three of the pieces of work being in operative relation to the swinging strip-carrying arms, 30, and the fourth being in an idle position 100 at the front of the machine. The main driving shaft is started and the clutch controller, 37, is depressed, causing the worm shaft to revolve. As soon as the main shaft begins to revolve, the belt, 6, rapidly rotates the three 105 pieces of work which are in operative relation to the abrading strip, so that the surfaces thereof are worn to produce on each a band or stripe. This continues during about the time it takes the group of gear 110 wheels 41, 42, 44, 45 and 47 to make one-quarter of a revolution. The gear wheels 42, 44 and 45 then reach such positions that they begin swinging the posts, 49, in a direction to carry the swinging strip-carrying arms 115 outwardly away from the work. When the strip has been carried clear of the work it will be found that the pawl, 64, has reached a position to cause the rotatable table to be released from its stop so that the table will 120 begin to revolve and will not again come to rest until it has traveled through an angle of ninety degrees, at which point the piece of work which is at the right in Fig. 2 will have been carried to the front of the machine. By the time the table has completed its quarter turn the swinging strip-carrying arms will have started to travel inwardly so as to bring the strip into operative relation to the three pieces of work in working 125 130

positions. The inward swinging of the arms, 30, is completed shortly after the table has been brought to rest by its automatic stop device. The workman then removes the 5 piece of work at the front of the machine and puts in a new piece. Of course, when the machine is first loaded, the table should be allowed to make a complete rotation before a piece of work is removed, in order to 10 permit each piece to pass through its three working positions. Thereafter, however, whenever the table stops, it presents a completed piece of work at the front side of the machine. It will be seen that each quarter 15 turn of the table corresponds to a complete rotation of the gear wheels 41, 42, 44, 45 and 47 so that after each quarter turn of the table the pin, 48, on the gear wheel 47 will engage with the clutch lever, 35, and cause 20 the clutch between the main driving shaft and the worm shaft to be thrown out. Consequently, while three of the pieces of work 25 may continue to rotate, the table cannot again start ahead until the operator presses down the manual clutch actuator, 37. It will also be seen that whenever the worm shaft is running it is operating the feed rolls for the strip, so that the strip is slowly 30 unwound from the spool.

30 While I have illustrated and described with particularity only a single preferred form of my invention, I do not desire to be limited to the exact structural details thus illustrated and described; but intend to 35 cover all forms and arrangements which come within the terms employed in the definitions of my invention constituting the appended claims.

I claim:

40 1. In combination, a rotatable table, a plurality of rotatable work supports mounted on said table, means for yieldingly holding a strip of abrading material against pieces of work in said holders, mechanism for moving said strip away from and then toward the work, and other mechanism co-ordinated with the aforesaid mechanism to rotate the table through an angular distance corresponding to the angular 45 distance between two consecutive holders while the strip is being held clear of the work.

50 2. In combination a rotatable table, a plurality of rotatable work supports mounted on said table, means for yieldingly holding a strip of abrading material against pieces of work in said holders, mechanism for moving said strip away from and then toward the work, other mechanism co- 55

dinated with the aforesaid mechanism to 60 rotate the table through an angular distance corresponding to the angular distance between two consecutive holders while the strip is being held clear of the work, and an automatic stop for bringing said mechanisms to rest after the table has moved through said angular distance. 65

3. In combination, a rotatable table, a series of rotatable work supports distributed around the table, a plurality of movable supports for receiving a strip of abrading material and holding it against pieces of work in all of the holders except one, mechanism for moving said supports from and toward the work, and other mechanism co-ordinated with the aforesaid mechanism to 70 rotate the table through an angle equal to the angular distance between consecutive work holders while the strip is being held clear of the work and then bring the table to 75 rest.

4. In combination, a rotatable table, a series of rotatable work supports distributed around the table, a plurality of movable supports for receiving a strip of abrading 80 material and holding it against pieces of work in all of the holders except one, mechanism for moving said supports from and toward the work, other mechanism co-ordinated with the aforesaid mechanism to 85 rotate the table through an angle equal to the angular distance between consecutive work holders while the strip is being held clear of the work and then bring the table to 90 rest, and means for stopping said mechanisms whenever the table has moved through 95 said angular distance.

5. In combination, a rotatable table, a series of rotatable work supports distributed around the table, a plurality of movable supports for receiving a strip of abrading material and holding it against pieces of work in all of the holders except one, mechanism for moving said supports from and toward the work, other mechanism co-ordinated with the aforesaid mechanism to 100 rotate the table through an angle equal to the angular distance between consecutive work holders while the strip is being held clear of the work and then bring the table to 105 rest, and means associated with one of said mechanisms for gradually feeding the strip of abrading material in the direction of its length.

In testimony whereof, I sign this specification.

HRANT G. ANTARAMIAN.
